UNITED STATES PATENT OFFICE.

CHARLES WIGHT SNYDER, OF HUDSON, NEW YORK.

INTERNAL-COMBUSTION ENGINE.

No. 918,211.

Specification of Letters Patent.

Patented April 13, 1909.

Application filed April 20, 1907. Serial No. 369,240.

To all whom it may concern:

Be it known that I, CHARLES WIGHT SNYDER, a citizen of the United States, and a resident of Hudson, in the county of Columbia and State of New York, have invented a new and Improved Internal-Combustion Engine, of which the following is a full, clear, and exact description.

This invention relates to certain improvements in internal combustion engines, and more particularly to two-cycle engines.

The object of the invention is to provide an improved construction of valve mechanism, whereby the exhaust gas may be more completely scavenged from the cylinder at the end of the explosion stroke and the fresh charge more effectively admitted thereto.

The invention consists in certain features of construction and combination of parts, all of which will be fully set forth hereinafter and particularly pointed out in the claims.

Reference is to be had to the accompanying drawings forming a part of this specification, in which similar characters of reference indicate corresponding parts in all the figures, and in which—

Figure 1 is a side elevation of an engine constructed in accordance with my invention; Fig. 2 is a central vertical section taken on the line 2—2 of Fig. 1; Fig. 3 is a transverse section taken on the line 3—3 of Fig. 2, the piston being removed; and Fig. 4 is a detail section similar to a portion of Fig. 2, but showing the parts in a different position.

In my improved engine I provide a cylinder 10 of any suitable form and provided with a jacket 11 or other suitable means for cooling. The cylinder is connected to any suitable form of crank case 12, within which operates the crank 13 and the piston rod 14, the latter being connected to any suitable form of piston 15 mounted within the cylinder. All of the parts above referred to may be constructed according to any well known design, inasmuch as the details thereof constitute no portion of my invention.

The engine is preferably so constructed that the fresh charge is compressed in the crank case before being delivered to the working cylinder, and to permit of this I provide a suitable inlet pipe 16 leading from the carburetor, not shown, to the crank case, and from the crank case a conduit 17 leads to the inlet port of the working cylinder.

If desired, the conduit 16 may communicate directly with the atmosphere, whereby only pure air is compressed in the crank case, and the conduit 17 may lead through the carburetor on its way to the inlet port, or may have means for delivering the liquid fuel thereto. The cylinder is provided with an inlet port 18 and an exhaust port 19 in the walls thereof, and both ports are preferably so located that they are uncovered by the piston at or adjacent the end of its working stroke, although the inlet port may, if desired, be formed at the opposite end of the cylinder and adjacent the spark plug 20. In the form of the invention illustrated in the accompanying drawings, the inlet port 18 and the exhaust port 19 are on opposite sides of the cylinder and are adapted to be uncovered simultaneously by the piston. The face of the piston is provided with an upwardly directed flange 21 extending across the same between the inlet and exhaust ports, whereby air or gas entering through the inlet port is directed toward the opposite end of the cylinder before being permitted to escape through the exhaust port.

In the specific form of my invention illustrated in the accompanying drawings, I provide means whereby either air or an explosive mixture may be admitted through a single inlet port, and whereby this port or the two separate conduits leading thereto may be so controlled that at the end of the explosion stroke the exhaust port is opened, fresh air is admitted to force out the exhaust gas, and then the fresh charge is admitted.

Adjacent the inlet port I provide a rotary three-way valve 22 adapted to control the passage through the inlet port 18, through the conduit 17 leading from the crank case or other explosive mixture compressor, and a third passage through a conduit 23 communicating with the outside atmosphere or with any suitable air compressor. This valve is preferably cylindrical in form at its ends, and intermediate its ends it is cut away to form a crescent-shaped portion 24 and adapted to place the inlet port 18 in communication with either the air passage 23 or the fuel mixture conduit 17. This valve is provided with a journal 25 at one end thereof having a bearing in the wall of the valve casing 30, and having a shaft 26 extending out through the engine frame at the opposite side and supporting a sprocket or gear wheel 27. This sprocket or gear wheel is operatively

connected to a corresponding sprocket or gear wheel 28 mounted upon the main drive shaft 29 of the engine, and the sprocket or gear 28 is preferably of just twice the size of 5 the sprocket 27, whereby the shaft 26 and valve 22 carried thereby rotate twice for each revolution of the crank shaft.

The inlet port 18 is preferably upon substantially the same level as the exhaust port 10 19, whereby they are uncovered simultaneously. The valve 22 and its valve casing 30 are preferably located closely adjacent the inlet port 18, and the valve casing is cut away to leave a recess 31 adjacent the passage leading to the inlet port 18, whereby the valve will not be closed before the piston closes said port.

In the operation of my improved engine, the parts will occupy the positions indicated 20 in Fig. 2 just before the end of the exhaust stroke, and the exhaust port 19 will be uncovered by the piston 15, whereby the exhaust gases can escape, but even though the inlet port 18 is open, the valve 22 is not rotated to a sufficient extent to permit of the escape of the exhaust through the conduit 23. Most of the exhaust gases escape at this instant, and as the piston progresses a 25 slightly greater distance, the rotation of the valve opens the conduit 23, and the inertia 30 of the gases passing through the exhaust port 19 and the conduit or muffler connected thereto, causes a suction and fresh air is drawn inward through the port 18 and into 35 the engine cylinder. If this inertia or suction is not sufficiently great, a compressor generating a small pressure, as, for instance, one-half to one pound, may be connected to the conduit 23, or a suction fan may be connected to the exhaust port 19. As the piston 40 travels to the end of its stroke the port 19 is completely uncovered and the conduit 23 is opened and in free communication with the interior of the cylinder, at which time the 45 cylinder is completely scavenged, the parts occupying the positions indicated in solid lines in Fig. 4. As the piston starts upon the return stroke, the conduit 23 is quickly closed and by the time the piston reaches the 50 position shown in dotted lines in Fig. 4, the valve is rotated to its position, also shown in dotted lines, and the interior of the engine cylinder is in free communication with the conduit 17. At this time the explosive mixture 55 which has been compressed in the crank case is forced upward into the engine cylinder until the piston is moved up to a sufficient distance to shut off communication, the recess 31 preventing the valve from closing before the port. The compression, ignition 60 and explosion are then effected as in an ordinary internal combustion engine. As the valve 22 rotates twice during each revolution of the main shaft 29, it is evident 65 that the conduits 23 and 17 are successively

placed in communication with the inlet port 18 while the piston is at the opposite end of the cylinder and at approximately the time when the explosion takes place, but as the valve is so constructed that it cannot place 70 the conduits 17 and 23 in communication with each other and as the port 18 is effectively closed by the flange of the piston at this time, the rotation of the valve is immaterial. 75

As the accompanying drawings illustrate only one embodiment of my invention, it is evident that various changes may be made in the construction thereof and within the scope of the appended claims, without departing from the spirit of the invention. 80

In the foregoing specification and in the claims, the term "explosive mixture" is used to designate the fluid delivered from the crank case through the conduit 17, but 85 by the term "explosive mixture" I do not wish to be limited to a mixture having the exact and theoretical proportions for producing perfect combustion. It may be desirable to deliver a somewhat richer mixture 90 through the conduit 17 than is normally desirable in an engine cylinder, as the air admitted through the conduit 23 and remaining in the cylinder will serve to dilute the charge. 95

Having thus described my invention, I claim as new and desire to secure by Letters Patent:

1. In an internal combustion engine, a working cylinder having an exhaust port, an air delivery conduit and an explosive mixture conduit communicating with said cylinder, and a single valve at the junction of said conduits for opening and closing said conduits independently and in succession. 100

2. In an internal combustion engine, a working cylinder having a single inlet port, an explosive mixture delivery conduit, and means operating to establish communication between said inlet port and the outside atmosphere and between said inlet port and said explosive mixture delivery conduit in succession. 110

3. In an internal combustion engine, a working cylinder having an exhaust port and a single inlet port, a piston for controlling said exhaust port, an explosive mixture conduit communicating with said inlet port, an air delivery conduit communicating with said inlet port and with a source of air supply under atmospheric pressure, and means independent of the piston for admitting air under atmospheric pressure and an explosive mixture under compression through said inlet port after said exhaust port is opened, whereby the inertia of the exhaust gases in escaping from said exhaust port draws in air under atmospheric pressure prior to the admission of the explosive mixture under compression. 115 120 125 130

4. In an internal combustion engine, a working cylinder having an inlet port and an exhaust port, means for controlling said last-mentioned port, and means for admitting air under atmospheric pressure and explosive mixture under compression to said inlet port in succession after the exhaust port is opened, whereby the inertia of the exhaust gases in escaping from said exhaust port draws in air under atmospheric pressure prior to the admission of the explosive mixture under compression. 45
5. In an internal combustion engine, a working cylinder having an inlet port, a piston within said cylinder and adapted to control said port, an air delivery conduit and an explosive mixture conduit communicating with said port, and means independent of the piston for opening and closing said conduits in succession. 50
6. In an internal combustion engine, a working cylinder having an inlet port, a piston within said cylinder and adapted to control said port, an air delivery conduit and an explosive mixture delivery conduit communicating with said port, and means for opening said conduits in succession while the inlet port is uncovered by the piston. 55
7. In an internal combustion engine, a working cylinder having an inlet port, a piston within said cylinder, a crank case adapted to serve as a compression chamber, an explosive mixture delivery conduit leading from said crank case to said inlet port, an air delivery conduit communicating with said inlet port, and means for opening said conduits in succession when the piston is adjacent the end of its power stroke. 60
8. In an internal combustion engine, a working cylinder having an inlet port, a piston within said cylinder and adapted to cover said port, two independent conduits leading to said inlet port, a rotary valve adapted to control both of said conduits, and means for rotating said valve to open the conduits during the final portion of the explosion stroke and the first portion of the compression stroke. 65
9. An internal combustion engine having a working cylinder provided with an inlet port and an exhaust port, a piston within said cylinder and adapted to control both of said ports, a crank case adapted to serve as a compression chamber, a conduit leading from said crank case to said inlet port, a second conduit communicating with said inlet port, and a rotary valve adjacent said inlet port and adapted to open and close said conduits in succession while the inlet port is uncovered by the piston. 70
10. In a two-cycle, internal combustion engine, a working cylinder having an exhaust port and an inlet port, a piston for controlling both of said ports, a chamber communicating with said inlet port, an air delivery conduit communicating with said chamber, and an explosive mixture conduit communicating with said chamber and valve mechanism for controlling said conduits. 75
11. In a two-cycle, internal combustion engine, a working cylinder having an exhaust port and an inlet port, a piston for controlling both of said ports, a chamber communicating with said inlet port, an air delivery conduit communicating with said chamber, an explosive mixture conduit communicating with said chamber, and valve mechanism for controlling the communication between said conduits and said chamber. 80

In testimony whereof I have signed my name to this specification in the presence of two subscribing witnesses.

CHARLES WIGHT SNYDER.
